UNITED STATES PATENT OFFICE.

CHARLES H. FRY, JR., OF BELLAIRE, OHIO, ASSIGNOR OF THREE-FOURTHS
TO CHARLES S. S. BARON, JAMES MADISON MARRING, AND JOHN B.
McCORMICK, OF SAME PLACE.

LANTERN.

SPECIFICATION forming part of Letters Patent No. 234,767, dated November 23, 1880.

Application filed October 14, 1880. (No model.)

To all whom it may concern:

Be it known that I, CHARLES HENRY FRY, junior, a citizen of the United States, residing at Bellaire, in the county of Belmont and State 5 of Ohio, have invented new and useful Improvements in Lanterns, of which the following is a specification.

My invention relates to improvements in hand-lanterns for burning hydrocarbon oils, the 10 objects of my improvements being to produce an effective draft for the burner and for the flame by a direct outside draft, in connection with a globe and an inside chimney, to prevent smoking in swinging the lantern, or when 15 suddenly raising and lowering it, and the extinguishment of the flame from sudden puffs of wind. These objects I accomplish by the lantern shown in the accompanying drawings, in which—

20 Figure I represents a vertical section of a complete lantern; Fig. II, a top view of the globe-band and the perforated chimney-band; Fig. III, an under view of the lantern-top, showing the perforated interior ventilating-cap and 25 the spring-arms thereof for holding the top of the chimney in place; Fig. IV, a section of the globe-band and its central perforated supporting-band for the chimney, and Fig. V a top view of the burner and oil-cup.

30 The cup tube or neck *a* rises centrally from the top of the oil-cup *b*, and the burner *a'* is provided with a jacket, *c*, which surrounds this cup-neck, so as to leave an annular space, *c'*, for the supply of air beneath the burner. The 35 jacket for this purpose does not descend to or join the top of said cup.

The cup-band *d* is provided with an interior upwardly-inclined ring, *d'*, rising from near the top of the cup to about the height of the 40 cup-neck *a*, and having a space, *e*, between its upper edge and the jacket, while the globe-band *f*, fitting within the cup-band *d*, is provided with a horizontal ring, *g*, extending inward and a short distance above the cup-band ring *d*, but leaving a wider space, *h*, between its inner edge and the said jacket than the space *e* formed by said upwardly-inclined ring, for a purpose to be presently stated.

The globe *i* is supported clear of and above

its band *f*, so as to leave an opening, *j*, all around 50 beneath the lower edge of the globe *i* from a quarter to a half inch wide, by three or more supports, *k*, soldered to said band, and upon the upper ends of which the globe rests by a bottom-edge shoulder, as shown in Fig. 1. This 55 opening *j* opens directly within the chamber of the globe, so that the air entering said opening will pass directly down through the top space, *h*, to give the necessary draft to the burner. This opening *j* is below the top of the 60 burner *a'* and above the said top space, *h*, which latter should be about a quarter of an inch wide, while the lower space, *e*, should be less. The object of this difference in the widths of 65 such spaces is to cause a puff of wind descending through the top space, *h*, to be arrested and caught by the lower ring, so as to break its force and allow it to rise and pass over the upper edge of said inclined ring and down through the lower space, *e*, with a uniform draft. In 70 this function such lower ring forms an annular trough beneath the top ring, to receive and check descending puffs of wind which enter through the side opening, *j*, and thus hold it so that it may gradually enter the draft-passage 75 to the base of the burner, and thus prevent the extinguishment of the flame by checking the passage of the wind into the chamber of the jacket. By this construction there will be no violent disturbance of the air as it passes to 80 the flame-slot through the usual openings in the burner.

The chimney *l* is held in place at its bottom upon a vertical perforated band, *m*, and upon the inner ends, *k'*, of the supports *k*, and this 85 perforated band is to give a direct draft in the flame-chamber of the chimney and to supply the flame with fresh air for steadyng the same. This perforated band is attached to and carried by the supports which hold both the globe and the 90 chimney, and it surrounds the base of the burner and forms a continuation of the jacket, which is attached to and depends from said burner. The chimney is preferably seated upon its supports outside of said perforated band, fitting 95 closely over it so as to give the necessary draft to the chimney direct from the side opening around the base of the globe, and to render

the flame steady by preventing the wind from striking forcibly upon the flame from said side openings. For this purpose said perforated band must be arranged in a horizontal plane 5 with said air-supply opening.

The construction by which I obtain the opening above the top of the globe-band, the descending draft-space for the burner, and the direct side draft for the flame and the chimney 10 gives a uniform supply of air to these parts and enables me to use the chimney with a direct side draft therefor above the top plate of the globe-band.

The top of the chimney is surrounded by an 15 interior ventilator, *n*, and rises therein, leaving a sufficient space between its top and the crown of said interior ventilator for the draft of the chimney. The perforations *v* of this ventilator are below the top of the chimney, 20 and are formed by scalloping its lower edge, so that the crown forms a closed cap for the chimney with a draft-space from a quarter to half an inch. This gives the advantage of preventing the air from the lantern-top openings 25 from descending the chimney in raising or swinging the lantern, or from sudden gusts, while the combined function of the upwardly-inclined cup-band ring, the horizontal ring of the globe-band, and the perforated chimney- 30 band serves to maintain a uniform draft, so that the flame is protected from above, below, and from the side. This interior ventilator is provided with spring-arms *p*, which are set to bear upon the outer side of the chimney to 35 hold it in place. The ventilator is itself held in place in the top *r* by being sprung in with the scallop-forming holds *s*, seated in a horizontal groove formed in said top, which is provided with ventilating-openings *u* above 40 the crown of the inner ventilator. A gust of wind therefore, entering these top openings, *u*, cannot descend the chimney, but must pass into the space between the globe and the chimney. This is an important advantage in the 45 use of an interior chimney, as a downward draft would so affect the flame as to constantly endanger the breaking of the chimney.

The chimney may be of the form of lamp-chimneys, but I prefer the form shown, having 50 a straight body and a contracted top, as giving satisfactory results. The construction set forth prevents the smoking of the chimney and gives a strong flame which is little affected by the sudden handling of the lantern.

55 The burner-jacket may be foraminous, but I prefer the imperforate jacket, so that the air entering the opening *j* must descend to the top of the oil-cup before it can reach the burner supply-chamber.

60 It is important that the annular space *h*, formed by the globe-band ring *g* and the openings *v* of the top interior ventilator, *n*, should be within the chamber of the globe and outside of the chimney, and that the side opening, *j*, and the perforated draft-band *m* for the chimney should be within the same horizontal

plane to produce the results described. It is also important that the cup-band ring *d'* should be of the form of a frustum of a cone standing inward farther than the top ring; otherwise the wind would pass with full force into the bottom chamber of the burner in puffs. 70

The lantern may be of any approved form; and as to the globe-guards, the top, the base, the device for fastening the globe-band, and the means for adjusting the wick, they may be as shown or of any approved construction. The globe is held secure upon its supports by the clamping action of the lantern-top. The burner may be either screw or socket, and the 80 oil-cup or base may be either fixed or sliding. I prefer also to use a non-hinged globe-band. The chimney and globe can be easily removed for cleaning by turning back the top upon its hinge. 85

I claim—

1. In a lantern, the combination of the globe-band, the globe *i*, and the supports *k*, attached to and rising from the globe-band, to form an opening, *j*, all round between the lower edge 90 of the globe and the top of the globe-band, substantially as and for the purpose set forth.

2. The combination, in a lantern, of the globe-band and the globe held upon supports *k*, attached to and rising from the globe-band, to 95 form an opening, *j*, all round between the lower edge of the globe and the top of the globe-band, with a chimney supported upon the perforated band and the supports *k'*, and having communication with said globe-base 100 opening above and outside the base of the burner, substantially as and for the purpose set forth.

3. The combination, in a lantern, of the globe-base opening *j*, formed substantially as set 105 forth, and a chimney supported upon the perforated band and the supports *k'*, and communicating with said globe-opening, with the globe-band ring *g* and the jacket *c*, depending from said burner beneath the means by which 110 said chimney is supported, and has communication with said globe-base opening, substantially as and for the purpose herein set forth.

4. The chimney, supported substantially as described, and forming a continuation of the 115 vertical walls of a perforated draft-band, *m*, in combination with a globe-base opening, *j*, formed in a horizontal plane with said vertical perforated band, substantially as and for the purpose set forth.

5. The upwardly-inclined cup-band ring *d'* and the horizontal globe-band ring *g*, in combination with the burner-jacket *c*, the chimney, supported substantially as described, and the base-opening *j*, communicating with said chimney and the air-supplying chamber formed by said jacket, the said upwardly-inclined ring forming a space around the jacket of less width than that formed by the globe-band in relation to said jacket, substantially as and 130 for the purpose set forth.

6. The combination, in a lantern having a

globe and chimney, and both having communication with a draft-opening, *j*, formed at the base of said globe, with an interior top ventilator having an imperforate crown over and near the chimney-top, and circumferential openings *v* below the top of the chimney, and the lantern-top provided with ventilating-openings *u* above the crown of said interior ventilator and communicating with the circumferential openings *v* of the latter, substantially as and for the purpose set forth.

7. The interior top ventilator provided with spring-arms *p* and secured within the lantern-top, substantially as and for the purpose set forth.

8. The globe-band provided with the ring *g*, the supports *k* *k'* for the globe and the chimney, and the perforated vertical band *m* for said chimney, in combination with a burner provided with a jacket, *c*, depending from its base in vertical line, or thereabout, with said perforated chimney-band, between which and

the inner edge of said ring the annular space *h* is formed, substantially as and for the purpose set forth.

9. The improved lantern herein described, in which the cup-band is provided with the upwardly-inclined ring *d'*, the globe-band with a horizontal ring, *g*, and the burner with the depending jacket *c*, the globe with the opening *j* around its base, the chimney with the vertical perforated band *m* at its base, and the interior top ventilator, *n*, provided with the imperforate crown, and the spring-arms *p*, all constructed and having the relation to each other substantially as and for the purpose set forth.

In testimony whereof I have hereunto set my hand in the presence of two subscribing witnesses.
